US0D1078992S

(12) **United States Design Patent** (10) **Patent No.:** **US D1,078,992 S**
(45) **Date of Patent:** **** Jun. 10, 2025**

(54) **SNORKEL TUBE**

(71) Applicant: **Jiangxi Rentong Swimming & Diving Products Co., Ltd.**, Ji'an (CN)

(72) Inventor: **Guoren Hu**, Jiangxi (CN)

(73) Assignee: **Jiangxi Rentong Swimming & Diving Products Co., Ltd.**, Ji'an (CN)

(**) Term: **15 Years**

(21) Appl. No.: **29/899,531**

(22) Filed: **Aug. 9, 2023**

(30) **Foreign Application Priority Data**

Jul. 31, 2023 (EM) 015029682-0001

(51) **LOC (15) Cl.** **29-02**

(52) **U.S. Cl.** **D24/110.5**

(57) **CLAIM**

The ornamental design for a snorkel tube as shown and described.

DESCRIPTION

FIG. 1 is a front, right and top perspective view of a snorkel tube, showing my design.

FIG. 2 is a rear, left and bottom perspective view thereof.

FIG. 3 is a front elevation view thereof.

FIG. 4 is a rear elevation view thereof.

FIG. 5 is a left side elevation view thereof.

FIG. 6 is a right side elevation view thereof.

FIG. 7 is a top plan view thereof.

FIG. 8 is a bottom plan view thereof; and,

FIG. 9 is an enlarged view of detail 9 in FIG. 1.

The broken lines depict portions of the snorkel tube that form no part of the claimed design.

The dot-dash broken lines in FIGS. 1 and 9 depict the boundaries of the enlargements that form no part of the claimed design.

1 Claim, 9 Drawing Sheets
